CLAIM

The ornamental design for an a-coil brush, as shown and described.

DESCRIPTION

FIG. 1 is a top perspective view of the brush;
FIG. 2 is a bottom perspective view of the brush;
FIG. 3 is a top view of the brush;
FIG. 4 is a bottom view of the brush;
FIG. 5 is a back view of the brush;
FIG. 6 is a front view of the brush;
FIG. 7 is a side view of the brush, where the left and right sides of the brush are mirror images;
FIG. 8 is a bottom perspective view of the brush with a flashlight connected thereto; and,
FIG. 9 is a close-up side view of the brush head.

(Continued)

The flashlight and the strap attaching the flashlight to the brush are shown in broken lines, are environmental, and form no part of the claimed design.

1 Claim, 4 Drawing Sheets
